SHOCK ABSORBER FOR SEATS

Albert Wesley Cliffe, Lansdowne, Ontario,
Canada

Application March 14, 1932. Serial No. 598,862

2 Claims. (Cl. 155—51)

This invention pertains to seat supports and more particularly to seat supports used on various types of farm implements and machinery.

The primary object of my invention is to provide a seat support of improved design and construction that will efficiently absorb all shocks that the vehicle may be subjected to.

A further object is to provide such a seat support of extreme simplicity in design that will be both efficient in operation and inexpensive to construct and is a distinct improvement in the art.

Other objects, advantages and features of the invention may appear from the detailed description, the appended claims and the accompanying drawing in which:

Fig. 1 is a side elevation of my invention.

Fig. 2 is a plan view of the same.

Fig. 3 is a perspective view of the base plate.

Fig. 4 is a sectional view of the block and base plate, showing another manner of attaching the same.

Referring to the drawing more particularly, in which similar characters designate corresponding parts, my invention comprises a base plate 10 having suitable holes 11 therein whereby the same is securely fastened to the chassis 12 of the vehicle upon which the improved support is to be mounted. One end of the said plate 10 is formed into hinge loops 13. A bar 14 having the seat 15 secured at its upper end is hingedly connected to the base plate 10 by a loop 16 at its lower end, said loop corresponding with the loops of the base plate. A pivot pin 17 engages the loops 13 and 16 and is held in position by a cotter pin 18. This provides a hinge like connection for the seat bar 14 allowing the same to have free motion vertically. The said bar is made from a length of spring steel, rectangular in cross-section and is formed into a partial elliptical curve 14a having a horizontal portion 14b and a depending end 14c on which the loop 16 is formed. The horizontal portion 14b normally rests on a block of rubber or other suitable material 19. The said block being fastened to the base plate by means of screws 20. This block of rubber is provided to absorb the shocks which the vehicle is subjected to while passing over rough ground. A U-shaped member 21 may be provided to prevent the seat from tilting too far forward. The said member being secured to the base plate 10 adjacent the end opposite the loops 13 and adapted to straddle the bar 14.

In Fig. 4, another manner of attaching the base plate and block 19 is shown. In this figure

the base plate 10 is attached to the chassis 12 by bolts 22 and the block 19 is attached to the base plate by small bolts 20.

It is believed from the description heretofore given of the present invention taken in connection with the drawing that it is entirely clear, the manner in which the seat and the seat supporting means may be mounted on the vehicle.

While I have shown the preferred embodiment of my invention it is understood that minor changes in the details of construction may be resorted to within the scope of what is claimed.

1. A seat supporting bar of spring steel angularly disposed toward the vehicle to which it is attached having a horizontal portion formed near the lower end with a loop depending therefrom at right angles thereto, a base plate having loops formed on one end to correspond with the loop of the seat bar, a pin fitted into the said loops forming a hinge like connection, and means to retain said pin in position in the loops, means to secure the said plate on the vehicle, a block of resilient material between the horizontal portion of the seat bar and the base plate to which it is secured, and a U-shaped member secured to the base, extending upwards over the seat bar preventing the same from tilting too far forward.

2. A spring seat for vehicles comprising a base plate, a spring bar angularly disposed towards the vehicle to which it is attached having its lower end pivotally attached to said base plate, said bar having a horizontal portion near its lower end, a block of resilient material disposed between said base plate and the horizontal portion of said bar and a U-shaped member straddling said bar and attached to said base plate for limiting the upward movement of said bar.

ALBERT WESLEY CLIFFE.
